(57) **CLAIM**

The ornamental design for a truck bumper component, as shown and described.

DESCRIPTION

FIG. 1 is a front perspective view of a truck bumper component showing a first embodiment of our new design; FIG. 2 is a front elevational view of the truck bumper component of FIG. 1;

FIG. 3 is a rear elevational view of the truck bumper component of FIG. 1;

FIG. 4 is a top plan view of the truck bumper component of FIG. 1;

FIG. 5 is a bottom plan view of the truck bumper component of FIG. 1;

FIG. 6 is a left side elevational view of the truck bumper component of FIG. 1;

FIG. 7 is a right side elevational view of the truck bumper component of FIG. 1;

FIG. 8 is a front perspective view of the truck bumper component showing a second embodiment of our new design;

FIG. 9 is a front elevational view of the truck bumper component of FIG. 8;

FIG. 10 is a rear elevational view of the truck bumper component of FIG. 8;

FIG. 11 is a top plan view of the truck bumper component of FIG. 8;

FIG. 12 is a bottom plan view of the truck bumper component of FIG. 8;

FIG. 13 is a left side elevational view of the truck bumper component of FIG. 8; and,

FIG. 14 is a right side elevational view of the truck bumper component of FIG. 8.
